W. W. OWEN

MEASURED SERVICE TELEPHONE SYSTEM

Original Filed June 14, 1919

Inventor
William Walter Owen.

Attala Hly

UNITED STATES PATENT OFFICE.

WILLIAM WALTER OWEN, OF OAK PARK, ILLINOIS, ASSIGNOR TO AUTOMATIC ELECTRIC COMPANY, OF CHICAGO, ILLINOIS, A CORPORATION OF ILLINOIS.

MEASURED-SERVICE TELEPHONE SYSTEM.

Application filed June 14, 1919. Serial No. 304,246. Renewed March 30, 1923.

To all whom it may concern:

Be it known that I, WILLIAM WALTER OWEN, a citizen of the United States of America, and a resident of Oak Park, in the county of Cook and State of Illinois, have invented certain new and useful Improvements in Measured-Service Telephone Systems, of which the following is a specification.

- 10 My invention relates in general to improvements in measured service telephone systems, and more specifically to an improved means for controlling a coin collect device of the coin first type in which a polarized relay is used to either collect or refund a coin deposited by a calling subscriber. The invention may be considered as an improvement on my pending application S. N. 304,245, filed June 14, 1919.
- 20 A coin collector of the type which may be used and which I have illustrated diagrammatically is shown and described in U. S. Letters Patent #1043219, granted November 5, 1912, to O. F. Forsberg. Although it will be understood that any desired type may be used.

Among the objects of my invention is to provide a simple device, common to the lines of pay station subscribers, which may be jointly controlled by the calling and called subscriber to collect a coin by one polarity of high voltage battery and which may be solely controlled by a calling subscriber to refund a coin by means of another polarity high voltage battery. I have inserted the coin controlling relays in the trunk lines leading from the line switches of the subscribers to the connector switches, the relay groups being therefore less in number than the calling lines. A further object is to maintain the talking circuit as free as possible from all impedance and resistances to provide an effective talking circuit. It will be understood and it will be seen that to interpose selector switches between the line switches and the connector switches shown will not in any way interfere with the operation of the system, and the group of controlling relays E may as well be inserted in the trunk to the selector as in the trunk to the connector.

In the figure of the drawing I have shown a calling station A equipped with a coin col-

lector such as that shown in the above mentioned patent having a magnet 2 adapted to be connected to the line circuit by the closure of the springs 3 and 4 when a coin is deposited. The springs 4 and 5 also open at this time to render the calling device operable, it having been shorted out by said springs until the coin is deposited.

When the calling subscriber removes his receiver to initiate a call, a circuit is completed for the line relay 6 of the individual line switch C to start the idle trunk selecting operation of said switch. Relay 6 closes a series circuit for the switching relay 7 and magnet 8 in series and also closes a direct circuit for magnet 8 to the private wiper 10, short circuiting relay 7. As long as the private wiper meets ground on test contacts of busy lines, magnet 8 operates as a buzzer to advance the wipers 9, 10 and 11 to the first idle trunk at which time relay 7 being no longer shorted by ground on wiper 10, energizes to disconnect relay 6 and ground from the line A and extends the line through to the line relays 12 and 13 of the seized connector H. The circuit closed by the energization of relay 7 may be traced from ground through relay 13, springs 14 and 15, springs 16, wiper 11, to and through the line of substation A, and back through wiper 9, springs 17 and 18, upper winding of relay 19, springs 20 and 21, and relay 12 to battery. It will be noticed that I have shown only a portion of a standard two wire connector switch of the Strowger type, the only difference being that I have provided a pair of line relays in place of the standard double wound relay common to such switches, and I have given to relay 13 the sole control of the release of the connection. This is done to insure the release of the switches should there be any leak to ground on the calling line, such as a low resistance magnet 2, which might cause a double wound relay to hold up in case the ground at the 'phone happened to be on the same side of the line as the winding of the line relay which is connected to battery. Thus relay 13 must always fall back when the line circuit is opened regardless of whether battery has been reversed or not and even through relay 12 may be held up by ground through magnet 2. The connector H it will be under-

100
105

stood comprises the usual rotary magnet, busy test and ringing equipment (not shown) and has direct access to the subscribers' lines.

6 Relay 12 upon energizing opens one point at springs 22 in the circuit of relay 24 and vertical magnet 23. Relay 13 closes the springs 26 to energize relay 25, which relay in turn opens the release magnet circuit at 10 springs 27 and 28, supplies ground to the holding trunk through springs 27 and 29, and prepares another point in the vertical magnet circuit at springs 30.

15 The ground supplied to the holding circuit through springs 27 and 29 flows through the winding of relay 31 of the group of relays E to battery, and on through springs 32 and 33, springs 34 and 35, and the lower winding of relay 19 to battery, and also 20 through wiper 10 and relay 7 to battery.

Thus relay 31 is energized, the line switch C is held in its operated position, and the lower winding of relay 19 is energized in opposition to its upper winding. Relay 25 25 31 requires the combined energization of both windings assisting each other to attract its armatures, which may then be held energized by the lower winding alone. Relay 31 closes a circuit at springs 36 and 37 for 30 the slow relay 41, which energizes to prepare a circuit for relay 40 at springs 39, and substitutes a new holding ground circuit through springs 42 and 33 for the line switch C and relay 19.

35 The calling subscriber may now by means of his calling device, first operate vertical magnet 23 to step the switch H to a desired level and then the rotary magnet (not shown) to step the wipers to a desired line, which is then automatically signalled by 40 means of the usual ringing equipment.

Assuming that the called line is idle, then 45 the called subscriber upon removing his receiver in response to the signal, operates the back ridge relay 43 in series with the called line to reverse the connections of relays 12 and 13 with regard to the talking circuit, relay 13 being now connected to the upper conductor and relay 12 to the lower conductor. This reversal of relay 12 and 13 reverses the flow of current in the calling end 50 of the line circuit and therefore through the upper winding of the polar relay 19 of the group E. Relay 19 now attracts its armatures to short circuit its upper winding to prevent further changes in current flow from 55 affecting its energization and prepares a circuit through springs 44 and 48 from the high potential battery M which circuit will later be completed.

60 Conversation will now be carried on over the heavy conductors shown, relays 19, 31 and 41 of the group E being held energized by the ground for the springs 27 and 29 of connector H.

As soon as conversation is completed, the release of the connection is initiated by the hanging up of the receiver at the calling station to open the line circuit and to therefore open the circuit of the line relays 12 and 13 of switch H.

It will be noticed that a circuit is still left closed from ground through coin collect magnet 2 at the substation and over the lower talking conductor through line relay 12 to battery and relay 12 may therefore hold up if magnet 2 is of low enough resistance. However, relay 13 always deenergizes as soon as the line is opened regardless of any leak to ground and opens the 80 circuit of relay 25. Relay 25 closes the circuit of the release magnet 50 of the connector switch H at springs 27 and 28 and opens springs 27 and 29 to remove ground from the release trunk to the relay 31 of 85 group E. Relay 31 falls back and closes a circuit from ground through springs 36 and 38, springs 39, relay 41 being still energized due to its slow action, and through relay 40 to battery. Relay 40, upon energizing, 90 supplies a new holding ground circuit for relay 19 and for relay 7 of the switch C through springs 46 and 35 before relay 41 has time to fall back, opens the talking circuit to the connector switch at springs 17 95 and 18 and at spring 16 and its back contact, and completes the previously prepared circuit from the battery M, through springs 44 and 48, springs 47 and 16, wiper 11, coin controlled springs 4 and 3 and magnet 2 to 100 ground. The current supplied by battery M is of such strength and polarity as to cause the magnet 2 to direct the coin into the collect chute and to thereby restore the springs 3, 4 and 5 to normal. The relay 41 which 105 falls back an instant after relay 31, opens the circuit of relay 40 at springs 39 so that relay 40 also falls back to remove ground from the release trunk to allow the line switch C and relay 19 to assume normal 110 position.

Now in case the called subscriber's line were busy, or he did not answer, or that his line is a free line, then the battery is not reversed over the talking circuit and relay 19 115 does not energize but leaves the battery N connected through springs 48 and 45 to spring 47. In a call of this sort, relay 31 operates in the same manner as in the previous call to energize relay 41 and when the calling man restores his receiver to normal then relay 31 operates the relay 40 in the same manner as before except that in this case the circuit closed by the springs 16 and 47 leads through springs 45 and 48 to battery N. The current which now flows through the magnet 2 from battery N is of such a strength and polarity as to tilt the armature of relay 2 to direct the coin into the refund chute where it can be recovered by 120 125 130

the calling man. It will be seen therefore that I have provided a very efficient method of controlling the collection or refunding of a coin in an automatic telephone system by 5 a series of relays common to the lines and controlled over a third conductor separate from the talking circuit.

Having fully described and ascertained the features and aspects of my invention, 10 what I consider to be new and desire to have protected by Letters Patent, will be pointed out in the appended claims.

What I claim as my invention is:

1. In a telephone system, a line, a coin 15 collector for said line in which a coin is deposited before a call and having means for collecting or refunding a deposited coin, a pair of automatic switches, one automatic switch for extending a talking circuit from said line to the other automatic switch, a pair of line relays for said other switch, one connected between one side of the talking circuit and battery and the other between the other side of the talking circuit and ground, 20 means controlled by the first relay for controlling the operation of said other automatic switch to further extend the connection, means controlled by the other relay for controlling the release of said first automatic 25 switch, and means individual to said second automatic switch controlled by said other relay over a portion of the release circuit of the first switch for controlling the operation of said first mentioned means to collect or 30 refund the coin.

2. In a telephone system, a line, a coin 35 collector for said line in which a coin is deposited before a call and having means for collecting or refunding a deposited coin, a pair of automatic switches, one automatic switch for extending a talking circuit from said line to the other automatic switch, a pair of line relays for said other switch, one connected between one side of the talking circuit and battery and the other between the other 40 side of the talking circuit and ground, means controlled by the first relay for controlling the operation of said other automatic switch to further extend the connection, means controlled by the other relay for controlling the release of said first automatic 45 switch, and means individual to said second automatic switch controlled by said other relay over a portion of the release circuit of the first switch for controlling the operation of said first mentioned means to collect or refund the coin when the calling subscriber opens the line circuit to release.

3. In a telephone system, a line, a coin 50 collector for said line in which a coin is deposited before a call and having means for collecting or refunding a deposited coin, a pair of automatic switches, one automatic switch for extending a talking circuit from said line to the other automatic switch, a pair

of line relays for said other switch, one connected between one side of the talking circuit and battery and the other between the other side of the talking circuit and ground, a positive and a negative battery of greater potential than that used to operate the automatic switches, means controlled by the first relay for controlling the operation of said other automatic switch to further extend the connection, means controlled by the other relay for controlling the release of said first automatic switch, and means individual to said second automatic switch controlled by said other relay over a portion of the release circuit of the first switch for controlling the operation of said first mentioned means to collect or refund the coin when the calling subscriber opens the line circuit to release by connecting said positive or negative battery to the magnet.

4. In a telephone system, a line, a coin collecting device for said line in which a coin is deposited before a call and having a magnet for operating the device to collect or refund the coin, an automatic switch for the line, a connector switch, a trunk line accessible to said automatic switch leading to said connector switch, a pair of line relays for the connector switch, means controlled over said line to operate one relay to control the connector to extend the connection and for operating the other relay to control the release of the automatic switch, a positive and a negative battery of higher potential than that used to operate the switches, a relay individual to said trunk line controlled over a conductor separate from the talking conductors by said last mentioned line relay to open the line circuit to the connector switch and to connect said higher potential positive or negative battery to the calling line over the trunk line to operate the magnet in one direction to collect the coin and in the other direction to refund the coin.

5. In a telephone system, a line, a coin collecting device for said line in which a coin is deposited before a call and having a magnet for operating the device to collect or refund the coin, an automatic switch for the line, a connector switch, a trunk line accessible to said automatic switch leading to said connector switch, a pair of line relays for the connector switch, means controlled over said line to operate one relay to control the connector to extend the connection and for operating the other relay to control the release of the automatic switch, a positive and a negative battery of higher potential than that used to operate the switches, a relay individual to said trunk line controlled over a conductor separate from the talking conductors by said last mentioned line relay to open the line circuit to the connector switch and to connect said higher

potential positive or negative battery to the calling line over the trunk line to operate the magnet in one direction to collect the coin and in the other direction to refund the coin, and means for preventing the release of the automatic switch until the coin is either collected or refunded also controlled by said last relay.

6. In a telephone system, a line, a coin collecting device for said line in which a coin is deposited before a call and having a magnet for operating the device to collect or refund the coin, an automatic switch for the line, a connector switch, a trunk line accessible to said automatic switch leading to said connector switch, a pair of line relays for the connector switch, means controlled over said line to operate one relay to control the connector to extend the connection and for operating the other relay to control the release of the automatic switch, a positive and a negative battery of higher potential than that used to operate the switches, a relay individual to said trunk line controlled over a conductor separate from the talking conductors by said last mentioned line relay to open the line circuit to the connector switch and to connect said higher potential positive or negative battery to the calling line over the trunk line to operate the magnet in one direction to collect the coin and in the other direction to refund the coin, and another relay controlled over the trunk line by the called subscriber for determining whether the coin is to be collected or refunded.

7. In a telephone system, a line, a coin collecting device for said line, a magnet for controlling the operation of the device, an automatic switch individual to the line, a plurality of other switches, said individual switch adapted to be operated automatically by the closure of the line to extend a talking circuit via any one of a plurality of trunk lines to any of said plurality of other automatic switches, a trunk release circuit controlled by the other automatic switch for controlling the release of said automatic switch, a battery for operating said automatic switches to which said magnet is non responsive, another battery of higher potential, means controlled over the talking circuit for preparing a circuit for the magnet to either pole of said high potential battery, and a relay individual to the trunk line in said talking circuit and controlled over said trunk release circuit for completing said prepared circuit to either collect or refund a coin.

8. In a telephone system, a line, a coin collecting device for said line, a magnet for controlling the operation of the device, an automatic switch individual to the line, a plurality of other automatic switches, a plurality of trunk lines, said first switch adapt-

ed to be operated automatically by the closure of the line to extend a talking circuit via any one of said plurality of trunk lines to any of said plurality of other automatic switches, a trunk release circuit controlled by the other automatic switch for controlling the release of said automatic switch, a battery for operating said automatic switches to which said magnet is non responsive, another battery of higher potential, means controlled over the talking circuit for preparing a circuit for the magnet to either pole of said high potential battery, and a relay individual to the trunk line in said talking circuit and controlled over said trunk release circuit for completing said prepared circuit to either collect or refund a coin and for preventing the release of the said automatic switch until the prepared circuit is closed and the coin either refunded or collected.

9. In a telephone system, a line, a coin collecting device for said line, having a magnet for collecting or refunding a pre-deposited coin, a connector switch, an automatic switch for the line for extending a talking circuit therefrom through said connector switch to a called line, a relay having a winding in the talking circuit and jointly controlled by the calling and called subscribers to determine whether a coin is to be collected or refunded, a trunk release circuit for the automatic switch controlled by the calling subscriber through the connector switch, and a relay common to a plurality of said automatic switches controlled over said release circuit solely by the calling subscriber for operating said magnet as determined by the called subscriber to either collect or refund the coin.

10. In a telephone system, a line, a coin collecting device for said line, having a magnet for collecting or refunding a pre-deposited coin, a connector switch, an automatic switch for the line for extending a talking circuit therefrom through said connector switch to a called line, a relay having a winding in the talking circuit and jointly controlled by the calling and called subscribers to determine whether a coin is to be collected or refunded, a trunk release circuit for the automatic switch controlled by the calling subscriber through the connector switch, and a relay common to a plurality of said automatic switches controlled over said release circuit solely by the calling subscriber for operating said magnet as determined by the called subscriber to either collect or refund the coin before the automatic switch is released.

11. In a telephone system, a line, a coin collecting device for said line, having a magnet for collecting or refunding a pre-deposited coin, a connector switch, an automatic switch for the line for extending a

5 talking circuit therefrom through said connector switch to a called line, a relay having a winding in the talking circuit and jointly controlled by the calling and called subscribers to determine whether a coin is to be collected or refunded, a trunk release circuit for the automatic switch controlled by the calling subscriber through the connector switch, and a relay common to a plurality 10 of said automatic switches controlled over said release circuit solely by the calling subscriber for operating said magnet as determined by the called subscriber to either collect or refund the coin by an impulse of 15 increased current.

12. In a telephone system, a line, a coin collecting device for the line, a magnet for controlling said device to collect or refund a coin, means including a series of automatic 20 switches for extending a talking circuit to a called line, a trunk release circuit for the first switch of said series separate from the talking circuit, and means controlled over

said trunk release circuit for first collecting or refunding a coin and then releasing the 25 first switch in the series.

13. In a telephone system, a line, a coin collecting device for the line, a magnet for controlling said device to collect or refund a coin, means including a series of automatic 30 switches for extending a talking circuit to a called line, a trunk release circuit for the first switch of said series separate from the talking circuit, means for releasing said talking circuit from the first switch to the 35 called line, and a relay controlled over said release circuit for momentarily holding the first switch from releasing after the talking circuit has been released and for closing a circuit for said magnet to collect or refund 40 the coin while the first switch is held from releasing.

Signed by me at Chicago, Cook County, Illinois, this 12th day of June, 1919.

WILLIAM WALTER OWEN.
